United States Patent Office

Des. 188,295
Patented June 28, 1960

188,295

FILLING MACHINE FOR ICE CREAM OR THE LIKE

Paul H. Carter, Thomas E. Marion, and Raymond L. Morse, Baltimore, Md., assignors to Universal Machine Co., Inc., Baltimore, Md., a corporation of Maryland

Filed Aug. 3, 1959, Ser. No. 57,045

Term of patent 14 years

(Cl. D55—1)

FIG. 1.

Des. 188,295

PAGE 2

FIG. 2.

Des. 188,295

PAGE 3

FIG. 3.

Des. 188,295

PAGE 4

FIG. 4.

FIG. 5.

Fig. 1 is a front elevational view of a filling machine for ice cream or the like showing our new design.

Fig. 2 is a rear elevational view thereof.

Fig. 3 is a left side elevational view thereof.

Fig. 4 is a right side elevational view thereof.

Fig. 5 is a plan view thereof.

The dominant features of our design reside in the portions shown in full lines.

We claim:

The ornamental design for a filling machine for ice cream or the like, as shown and described.
